DESIGN FOR A DRAWER PULL

John Weber, Milton, Pa., assignor to Lewisburg
Chair and Furniture Company, Lewisburg,
Pa., a corporation of Pennsylvania

Application June 24, 1936, Serial No. 63,468

Term of patent 3½ years

To all whom it may concern:

Be it known that I, John Weber, a citizen of the United States, residing at No. 527 North Front Street, in the city of Milton, county of Northumberland, and State of Pennsylvania, have invented a new, original, and ornamental Design for Drawer Pulls, of which the following is a specification, reference being had to the accompanying drawing, forming part thereof.

Figure 1 is a perspective view of the drawer pull showing my new design.

Figure 2 is an end elevational view thereof.

I claim:

The ornamental design for a drawer pull, as shown.

JOHN WEBER.
